UNITED STATES PATENT OFFICE.

RICHARD L. BARRETT, OF CHICAGO, ILLINOIS.

GREASE CUP.

Application filed October 8, 1923. Serial No. 667,176.

To all whom it may concern:

Be it known that I, RICHARD L. BARRETT, a citizen of the United States, residing at Chicago, in the county of Cook and State of Illinois, have invented certain new and useful Improvements in Grease Cups, of which the following is a specification.

This invention relates to improvements in grease cups of the type embodying a cup having a plunger therein provided with screw threads adapted to engage threads carried by the cup and having connected with the cap a skirt which is adapted to be freely slipped over the cup to closely fit the periphery of the cup, whereby the plunger when outside of the cup will be properly positioned so that the threads thereon will properly engage the threads of the cup. One of the objects of the present invention is to provide an improved means for locking the cap and skirt in position and improved means whereby a tension will be exerted upon the plunger when outside of the cup to cause the threads on the plunger to engage the threads in the cup without necessitating manual pressure upon the plunger, and at the same time insure against an improper alinement and a cutting or a stripping of the threads.

A further object is to provide an improved device of this character embodying a hollow manually adjustable plunger, there being a spring controlled plunger operating in the hollow plunger and which spring controlled plunger is yieldable to the resistance of the grease so as to store energy in the spring controlled plunger to automatically feed the grease after the manually adjustable plunger has been adjusted to place under tension the spring which controls the other plunger, thereby rendering it possible to cause the grease or lubricant to be automatically fed to the part to be lubricated while the latter is in motion or operation.

To the attainment of these ends and the accomplishment of other new and useful objects as will appear, the invention consists in the features of novelty in substantially the construction, combination and arrangement of the several parts and hereinafter more fully described and claimed and shown in the accompanying drawing illustrating this invention, and in which

Figure 1 is a perspective view of a grease cup of this character constructed in accordance with the principles of this invention.

Figure 2 is a side elevation on an enlarged scale, partly broken away and partly in section, showing one position of the parts and with the plungers outside of the cup 60 and in position so that the threads on one plunger will engage the threads in the cup.

Figure 3 is a view similar to Figure 2, showing the plunger in another position with the spring controlled plunger displaced 65 and under tension.

Figure 4 is a detail sectional view taken on line 4-4, Figure 2.

Figure 5 is an enlarged detail sectional view, showing the manner of locking the 70 cap in position upon the cup.

Referring more particularly to the drawing the numeral 10 designates a grease cup of any desired size and external configuration, having a threaded stem or portion 11, 75 through the medium of which the cup may be secured to a suitable part by means of an angular portion 12 on the stem and which angular portion is adapted to receive a wrench or tool, all as usual in grease cups 80 of this character.

The cup is provided with internal screw threads 13 and is also provided with an outlet opening 14, through which the grease is forced from the cup.

A cap 15 is also provided, the internal diameter of a portion of which cap is slightly greater than the external diameter of the cup 10, so that the cap 15 may be passed over the cup 10. This cap 15 is provided with an end 16 which is closed except for an opening 17 located centrally thereof and surrounding the opening is a collar or flange 18, forming an extended guide for a plunger 19, the body portion of which plunger is 95 adapted to pass freely through the opening 17.

One end of the plunger is enlarged as at 20 and this enlarged portion is of a diameter slightly less than the interior diameter of the cup 10. The enlarged portion 20 is provided with peripheral screw threads 21 which are adapted to engage the threads 13 on the interior of the cup 10, so that when the plunger 19 is rotated by means of a suitable handle 22, the threads 21 on the portion 20 of the plunger will engage the threads 13 of the cup and will cause the plunger to be advanced or retracted, according to the direction of rotation of the plunger. The handle 22 may be of any desired configuration but is preferably of a cup shape forma-

tion, constructed of a single piece of material formed into shape. The plunger 19 is preferably tubular and is provided with reduced portions adapted to pass through suitable openings in the handle 22 and the extremities of the reduced portions are upset as at 23 for securing these parts together.

The cap 15 extends for any desired distance above the bottom of the cup 10 and has provided therein a recess 24, into which the enlarged portion 20 of the plunger is adapted to enter so that the threads on the portion 20 may be entirely disengaged from the threads 13 in the cup to permit the cap 15 and plunger 19 to be removed as a unit from the cup when desired. The height of the recess 24 is only slightly greater than the height of the portion 20 of the plunger containing the screw threads 21, so that when the screw threads 21 have been entirely disengaged from the threads 13 of the cup 10, the enlarged portion 20 of the plunger will fill the space 24.

The cap 15 may be detachably secured to the cup 10 in any desired or suitable manner, but preferably by means of a bayonet slot connection embodying one or more bayonet slots 25, and one or more pins 26, projecting beyond the outer wall of the cup 10, so that when the cap 15 is placed in position the pins 26 will enter the bayonet slots 25 and after the cap is rotated with respect to the cup, the parts will be locked together.

The body of the cap or skirt 15 is split as at 27, within the confines of the edges of the cap, and the split portion 27 communicates with the bayonet slot 25. One of these split portions or slots may be provided adjacent each of the bayonet slots 25 and are provided for the purpose of causing a portion of the cap or skirt 15 to be resilient so that when the plunger 19 assumes the position shown in Figure 2, with the threads 21 on the portion 20 of the plunger entirely disengaged from the threads 13 of the cup 10 and with the plunger disposed entirely within the recess or space 24, the resilient portion 28 of the cap will be placed under tension and this tension will tend to hold the lower edge of the enlarged portion 20 of the plunger 19 against the edge of the cup 10 and in such a position that when the plunger 19 is rotated by the handle 22 the threads 21 will be properly positioned to engage the threads 13 of the cup 10. This will obviate a mutilation, cutting or stripping of the threads. Furthermore when the cup is full of grease and the parts are in the position shown in Figure 2, the resilient portions 28 of the cap or skirt 15 also operate to draw the plunger toward the cup, so that it will not be necessary to exert a manual pressure upon the end of the plunger 19 to cause the co-operating threads to start to engage. In other words, the resilient portions 28 of the

cap 15 serve as a means for automatically causing the threads 21 on the plunger 19 to engage the threads 13 in the cup 10 when the plunger is rotated.

Obviously any number of these bayonet 70 slots 25, slots 27 and resilient portions 28 may be employed.

Disposed within the hollow plunger 19 is a supplemental plunger or follower which preferably embodies a cup shaped member 29 of a diameter to snugly fit within the plunger. A washer 30 preferably of leather or any other suitable material, is secured to the bottom of the element 29, preferably by means of a fastening device 31 such as a 75 rivet or the like which passes through a disc 32, the washer 30 and the element 29, and between which disc 32 and element 29 the washer 30 is located.

The washer 30 is of a diameter somewhat 85 larger than the internal diameter of the plunger 19 so that when the washer is placed within plunger, the periphery 33 of the washer will be deflected as shown to cause the washer 30 to assume a cup shape formation. 90

Interposed between the handle 22 of the plunger 19 and the element 29 is an elastic member 34, preferably in the form of a coil spring, one end of which engages the handle 95 and the other end is seated within the element 29. This spring 34 tends normally to move the supplemental plunger toward the open end of the plunger 19 and thereby 100 close the opening in the plunger. As a means for preventing displacement of the supplemental plunger there may be provided a resilient split ring 35, which latter is adapted to be seated within a recess 36 within the plunger 19. The element 35 also 105 serves as a means for holding the deflected periphery 33 of the washer 30 in contact with the wall of the plunger 19 to form a liquid tight joint and thereby prevent the 110 grease or liquid from passing into the plunger 19 above the supplemental piston.

When the plunger 19 is rotated the supplemental plunger will also be rotated.

With this improved construction it will be manifest that when the parts are in the 115 position shown in Figure 2, and assuming that the cup 10 is filled with grease, when the plunger 19 is rotated the screw threads 21 engaging the threads 13 will cause the plunger 19 to be advanced within the cup. As the plunger 19 advances the advancing movement of the supplemental plunger will be retarded by the grease within the cup as 120 shown more clearly in Figure 3. The advancement of the plunger 19 and the retarding of the advancing movement of the supplemental plunger will result in the spring 34 being compressed so as to store energy 125 therein, with the result that the grease within the cup is placed under pressure by rea- 130

son of the supplemental plunger after the plunger 19 has been advanced to the desired distance. As the grease is utilized, it will be automatically fed through the opening 5 14 by means of the supplemental plunger influenced by the energy stored in the spring 34, with the result that there will be an automatic feeding of the lubricant to the part to be lubricated, while the latter is in operation 10 or in motion. This will insure a proper lubrication of the parts. The plunger 19 may be adjusted to any desired extent to cause the spring 34 to be compressed to the desired amount and any suitable means may 15 be provided for limiting the extent of movement of the supplemental plunger with respect to the plunger 19, when the latter is being adjusted into the cup. A suitable and efficient means for accomplishing this result 20 consists of a collar 37, which may be placed within the plunger 19. This collar may be of any desired height and is adapted to be engaged by the element 19 when the parts assume the position as shown in Figure 3.

25 The pins 26 may be formed in any suitable manner, but preferably by means of a bar or rod driven through the wall of the cup with the ends of the bar projecting beyond the outer wall of the cup, as shown 30 more clearly in Figure 5.

With this improved construction it will be manifest that the plunger 19 may be manually adjusted to acquire the desired tension upon the spring controlling the supplemental plunger and after the plunger 19 has been adjusted or set the lubricant will be automatically fed from the grease cup as it is consumed. Furthermore, the parts are so constructed that they may be all 35 formed from stampings or castings, thereby reducing to a minimum the machine work necessary on devices of this character.

40 While the preferred form of the invention has been herein shown and described, it is to be understood that various changes may be made in the details of construction and in the combination and arrangement of the several parts, within the scope of the claims, without departing from the spirit of this invention.

45 What is claimed as new is:—

1. A grease cup embodying a cup proper having internal screw threads, a cap for the cup, means detachably securing the cap in 50 position, a plunger operable in the cup and having threads adapted to engage the threads in the cup, there being an opening in the cap through which the plunger freely slides, and interengaging means on the cap and cup for detachably securing the parts together, the threaded portion of the plunger adapted to disengage from the threads in the cup and assume a position within the cap beyond the end of the cup, said interengaging means exerting a tension upon the

plunger when the said threaded parts are disengaged to insure a proper initial positioning of the threads with respect to each other.

2. A grease cup embodying a cup proper, 70 a cap therefor and into which cap the cup telescopes, interengaging means on the cap and cup for detachably securing the parts together, a plunger operable in the cup, said plunger extending through the cup, means 75 for operating the plunger from the outside of the cap, and threads on the plunger and in the cup adapted to interengage, the threaded portion of the plunger adapted to entirely disengage from the threads in the 80 cup and assume a position within the cap beyond the end of the cup, the first recited means embodying a bayonet joint connection between the cap and cup, a portion of the body of the cap being resilient and operating 85 through said interengaging means to hold the threaded portion of the plunger against the end of the cup.

3. A grease cup embodying a cup proper, 90 a cap therefor and into which cap the cup telescopes, interengaging means on the cap and cup for detachably securing the parts together, a plunger operable in the cup, said plunger extending through the cup, means 95 for operating the plunger from the outside of the cap, and threads on the plunger and in the cup adapted to interengage, the threaded portion of the plunger adapted to entirely disengage the threads in the cup and assume a position within the cap and beyond the end of the cup, the first recited means embodying a bayonet joint connection 100 between the cap and cup, a portion of the cap adjacent the said bayonet joint being split to form a resilient portion for exerting a stress through said interengaging means upon the plunger.

4. A grease cup embodying a cup proper, 110 a cap therefor and into which the cup telescopes, an open ended hollow plunger movable in the cup and extending through the cap, means whereby the rotation of the plunger will cause the same to advance within the cup, a follower movable within 115 the plunger and forming a closure for the open end of the latter, a spring disposed within the plunger and operating upon the follower, the said spring being placed under tension by the material in the cup when the plunger is advanced in the cup, said follower embodying a cup shaped flexible washer, and a removable annular element adjacent the 120 end of the plunger to be engaged by the periphery of the said washer, said element arresting the movement of the follower under the stress of the said spring and also operating to hold the periphery of the washer against the wall of the plunger.

5. A grease cup embodying a cup proper, 125 a cap therefor and into which the cup tele-

scopes, an open ended hollow plunger movable in the cup and extending through the cap, means whereby the rotation of the plunger will cause the same to advance within the cup, a follower movable within the plunger and forming a closure for the open end of the latter, a spring disposed within the plunger and operating upon the follower, the said spring being placed under tension by the material in the cup when the

plunger is advanced in the cup, and an annular element disposed within the plunger between the said follower and the open end of the plunger for limiting the movement of the follower with respect to the plunger ¹⁵ against the stress of the said spring.

In testimony whereof I have signed my name to this specification, on this 6th day of October, A. D. 1923.

RICHARD L. BARRETT.
